Primary Examiner — Manpreet Matharu*Assistant Examiner* — Mojtaba Tehrani(74) *Attorney, Agent, or Firm* — Reising Ethington P.C.(57) **CLAIM**

The ornamental design for a vehicle front fender, as shown and described.

DESCRIPTION

FIG. 1 is a perspective view of the vehicle front fender, showing our new design;

FIG. 2 is a side elevation view thereof;

FIG. 3 is a front view thereof; and,

FIG. 4 is a top view thereof.

The broken lines shown in the drawings depict portions of the vehicle front fender that form no part of the claimed design.
